(57) **CLAIM**

The ornamental design for an incubator analyzer, as shown and described.

DESCRIPTION

FIG. 1 is a top front right perspective view of an incubator analyzer showing our new design, wherein four sensor stands are shown inserted into slots in the incubator analyzer.

FIG. 2 is a top plan view thereof.

FIG. 3 is a front elevational view thereof.

FIG. 4 is a right side elevational view thereof.

FIG. 5 is a left side elevational view thereof.

FIG. 6 is a rear elevational view thereof.

FIG. 7 is a bottom plan view thereof; and,

FIG. 8 is a top front right exploded perspective view of the incubator analyzer shown in FIG. 1, wherein one of the four sensor stands is shown removed from one of the slots in the incubator analyzer.

The broken lines in the figures illustrate portions of the incubator analyzer that form no part of the claimed design.
